(57) **CLAIM**

The ornamental design for the “joint for sliding roofs for trucks,” as shown and described.

DESCRIPTION

FIG. 1 is perspective view of a joint for sliding roofs for trucks.

FIG. 2 is a front elevational view of the joint of FIG. 1.

FIG. 3 is a back elevational view of the joint of FIG. 1.

FIG. 4 is a top plan view of the joint of FIG. 1.

FIG. 5 is a bottom plan view of the joint of FIG. 1.

FIG. 6 is a left side elevational view of the joint of FIG. 1.

FIG. 7 is a right side elevational view of the joint of FIG. 1; and,

FIG. 8 is an alternative perspective view of the joint of FIG. 1. The broken line portion of the figure drawing is included to show portions of the article that forms no part of the claimed design.
